US00D963166S

(12) **United States Design Patent** (10) **Patent No.:** **US D963,166 S**
(45) **Date of Patent:** **** Sep. 6, 2022**

(54) **ALLOGRAFT INSERTION DEVICE**

(71) Applicant: **Board of Regents, The University of Texas System**, Austin, TX (US)

(72) Inventors: **Salman N Khan**, Bellflower, CA (US);
Panayiotis S Shiakolas, Irving, TX (US)

(73) Assignee: **BOARD OF REGENTS, THE UNIVERSITY OF TEXAS SYSTEM**, Austin, TX (US)

(**) Term: **15 Years**

(21) Appl. No.: **29/692,224**

(22) Filed: **May 23, 2019**

Related U.S. Application Data

(62) Division of application No. 29/574,341, filed on Aug. 15, 2016, now Pat. No. Des. 940,865.

(57) **CLAIM**

The ornamental design for an allograft insertion device, as shown and described.

DESCRIPTION

FIG. 1 is a front perspective view of an allograft insertion device according to an embodiment;

FIG. 2 is a rear perspective view thereof, opposite the view of FIG. 1;

FIG. 3 is a bottom plan view thereof;

FIG. 4 is a top plan view thereof, opposite the view of FIG. 3;

FIG. 5 is a front view thereof;

FIG. 6 is a rear view thereof, opposite the view of FIG. 5;

FIG. 7 is a right side view thereof; and,

FIG. 8 is a left side view thereof, opposite the view of FIG. 7.

(Continued)

The broken lines illustrate portions of the allograft insertion device and form no part of the claimed design.

1 Claim, 6 Drawing Sheets
